UNITED STATES PATENT OFFICE.

A HENRY MUSCATE, OF MANITOU, COLORADO.

AUTOMOBILE MEMO.

Application filed July 16, 1926. Serial No. 122,903.

This invention relates to an improved product of manufacture which may be conveniently referred to as an automobile memo, the same having more particular reference 5 to a device of this kind which is in the form of an attachment for an automobile steering post to dispose the attachment in a position to permit it to be conveniently viewed while driving.

10 Briefly, the invention has reference to an attachment of this kind which includes a casing for a memorandum pad, the casing being provided with a glass panel through which the writing on the pad may be viewed 15 while driving, and novel ejector mechanism being arranged in the casing for aiding in removing the pad.

The features and advantages of the invention will become more plainly apparent from 20 the following description and drawings.

In the accompanying drawings wherein like reference characters are employed to designate like parts throughout the same:

25 Figure 1 is a side view of a device constructed in accordance with the present invention.

Figure 2 is an enlarged top plan view of the device removed from the steering wheel.

30 Figure 3 is a horizontal section taken approximately upon the plane of the line 3—3 of Figure 2.

Figure 4 is a central longitudinal section through the structure showing the details in relative association more plainly.

35 Figure 5 is a perspective view of one of the details.

Figure 6 is likewise a perspective view of another one of the details, and

40 Figure 7 is a fragmentary detail sectional view.

The device is generally designated by the reference character 1 and an attaching clamp therefor is designated by the reference character 2. This is of a conventional form and 45 is connected with a substantially T-shaped bracket 3 which the device carries.

45 The device 1 comprises a substantially rectangular casing 4 which is open at one end to permit insertion and removal of the 50 memorandum pad 5. In practice this pad is rested upon a shelf 6 formed on the lower end of a follower plate 7 which is slidably mounted in the casing. It will be noticed from Figure 5 this follower plate is provided 55 with a downwardly struck portion 8 which is spaced below the shelf 6 and then by re-

ferring to Figure 4 it will be seen that a spring arm 9 is fastened in the casing as at 10 and has one end engaged with the part 8. The natural resiliency of the strip 9 serves 60 to return the follower to a predetermined position in an obvious manner. Attention is also directed to the fact that the resilient arm or spring 9 is provided adjacent its free end with an opening through which the 65 lower hooked ends of the arms of a wire link 12 pass and are connected. This link is of general U-shaped form, and the bight portion is connected to a bracket 13 on the under side of a lid 14 which is hingedly connected to the casing as at 15. It is yet to be pointed out that the front face of the casing is open and a glass panel 16 is employed for closing it. Thus permitting the inscription on the pad to be easily read through 70 this window. At this time I would direct attention to the fact that the length of the link 12 is such that when the cover or lid 14 is swung to open position as represented in Figure 4, it exerts an upward pull on the 80 spring 9, and thus acts as an ejector for the follower plate 7. Obviously, this lifts the pad upwardly so that it may be readily grasped to be removed from the follower plate. In this connection it will be noted 85 that one end or corner of the follower plate is notched or cut away to facilitate grasping of the pad in the fingers.

In practice it is obvious that the clamp 2 encircles the steering post or steering post 90 casing as represented in Figure 1, thus disposing the memorandum device 1 in a substantially inclined horizontal position beneath the steering wheel. The transparent side of course is disposed upwardly so that 95 the inscription on the pad may be readily viewed through the window. Consequently, the device will always be in a position to permit the notation to be borne in mind while driving. The device will be found 100 exceptionally successful for use by doctors. For instance, the clerk in the doctor's office may take phone calls, and make notations on the pad, and when the doctor is leaving the office he will hand this pad to him and he will insert it in the carrying casing on the steering post so that each item may be attended to in proper order. Then too, the device will be found successful for the housewife who drives downtown and has notations on the pad for various stops or calls 105 to make in attending to a business trip. In 110

fact, various other uses can be found for such a device and in view of the simplicity and practicability it is believed to be exceptionally advantageous and novel.

5 Undoubtedly, a careful consideration of the description in connection with the drawings will enable a clear comprehension of the invention to be had. Therefore, a more lengthy description is thought unnecessary.

10 While the preferred embodiment of the invention has been shown and described, it is to be understood that minor changes coming within the field of invention claimed may be resorted to if desired.

15 Having thus described the invention, what I claim as new and desire to secure by Letters Patent is:—

20 1. In a structure of the class described, a casing open at one end, a follower plate in said casing including a shelf upon which a pad is adapted to be supported, a tongue carried by the shelf equipped end of the follower plate, a spring arm anchored at one end to said casing and having its opposite 25 end cooperable with said tongue, a hingedly

mounted closure plate for the open end of the casing, and a connection between the closure plate and free end of the spring arm for sliding said follower plate in opposite directions.

30 2. In a structure of the class described, a casing open at one end, a follower plate slidably mounted in said casing and provided at its inner end with a right angularly disposed shelf upon which a writing pad is adapted to be supported, a tongue carried by said plate and spaced from said shelf, a spring arm anchored at one end in the casing and having its opposite free end engaged with said tongue, a hingedly mounted closure plate for the open end of the casing and a connecting length between the hinged end of said closure plate and the free end of the spring arm for sliding said follower plate upwardly and through the open end of the 40 casing when the closure plate is swung to open position.

45 In testimony whereof I affix my signature.

A HENRY MUSCATE.
